UNITED STATES PATENT OFFICE.

A. AUGUSTUS LOW, OF BROOKLYN, ASSIGNOR TO THE ALDEN TYPE MACHINE COMPANY, OF NEW YORK, N. Y.

TYPE-CONTAINING CHANNEL.

SPECIFICATION forming part of Letters Patent No. 360,358, dated March 29, 1887.

Application filed June 3, 1886. Serial No. 204,085. (No model.)

To all whom it may concern:

Be it known that I, A. AUGUSTUS LOW, a citizen of the United States, residing in the city of Brooklyn, in the county of Kings and 5 State of New York, have invented certain new and useful Improvements in Type-Containing Channels, of which the following is a full, clear, and exact description, sufficient to enable others skilled in the art to which the invention appertains to make and use the same.

My improvements, although applicable generally to type-channels of various kinds, relate more especially to the type-containing channels used in conjunction with the means 15 of setting and distributing type heretofore patented to Louis K. Johnson and myself, as set forth in Patents Nos. 230,784, 254,019, 271,711, 336,719, 264,085, 282,988, 336,645, 337,406, and 340,124, and subsequent applications for patents.

The type-containing channels of this class are transferable or interchangeable in and between both setter and distributor. When in the distributor, the receiving ends of the 25 containing-channels connect with permanent type-conduits, by which the types are deposited in the channels in prescribed positions, the types being successively forwarded in the containing-channels by a reciprocating 30 pusher, the pusher-fingers of which, when advanced, carry the last types deposited beyond the path of the heels of the succeeding types, so that the "throats" or type-receiving areas are left free and unobstructed. Practically, 35 in distribution this feature of maintaining an open free throat or receiving-space in each containing-channel is of importance, and to this end various means have been devised by the said Johnson and myself for preventing 40 or counteracting the "backlash" or retractile movement of the types into the throat after the receding type-pusher. In this connection reference may be had to earlier patents for an understanding of the nature and causes of 45 backlash and the means employed to obviate the difficulty, by which it will be seen that a type holding and resisting surface consisting of a continuous strip of a comparatively soft semi-elastic material is first used upon the 50 side wall of a channel at its receiving end for the purpose of obviating backlash, &c.

I have heretofore described and claimed various modifications in the use and application of such soft semi-elastic material for the purpose stated, and also for the purpose of regulating 55 the frictional contact of the type-preceders or "slugs" with the inner side walls of the channels.

Experience has demonstrated that in many respects the most effective as well as economical method of using the soft or semi-elastic holding and sustaining surface referred to is to apply it to the channels in the form of a suitable length of cord or string—that is to say, by exposing a section of cord in the channel between two perforations in the side wall, the end of the cord nearest the extremity of the channel being knotted to hold the cord against the strain caused by the types as they are forwarded, and the other end, after being 65 passed through the last perforation, being left 70 loose and free, so that the cord can adapt itself to any back-pressure exerted by the column of type, and by kinking or puckering up under such action increase the lateral pressure and promptly check any further retractile 75 movement.

My present invention relates in this last reference to the special construction herein set forth for facilitating the application or removal 80 and substitution of the lengths or sections of cord or string to the channel; and it consists in forming the extreme end of the channel with a slit in lieu of the perforation in the spine of the channel heretofore used, in which 85 the knotted end of the cord may be more readily secured, and in forming the side wall of the channel with a longitudinal slot coinciding in position with the bearing-surface of the cord when the latter is in position upon the 90 opposite side wall. This elongated slot provides for the convenient and rapid insertion or removal of the free end of the cord through the perforations in the opposite side wall, the narrowest of the type-channels heretofore rendering the operation tedious and difficult, 95 since the position of the cord within the channel is preferably about one-half of type-high, or near the middle height of the high wall of the channel, corresponding to the plane of action of the type-forwarding device when the 100 channel is in position in the distributor.

In my applications hereinbefore referred to I show several methods of applying a comparatively soft semi-elastic frictional surface to the type-preceders or slugs in such manner as to increase the frictional contact with the side walls of the channels; but such means necessarily imply the use of a preceder or slug of less thickness than the width of the type-passage.

- 10 My present invention includes a type-preceder or slug the perimeter of which is provided with a surface or band of comparatively soft elastic or semi-elastic material for increasing frictional contact with the bottom or spine of the channel. By this construction I am enabled to attain the requisite degree of friction or resistance and still use a close-fitting preceder or slug of a thickness equal (nearly) to the width of the type-channel. I 15 also utilize the weight of the slug in pressing the frictional material against the bottom or spine, and thereby increase its effectiveness to that extent.

20 My invention also includes the formation of the side wall of the channel with a shallow groove or depression for the reception of the cord, the sides of which groove support the cord laterally, while permitting it to project into the channel sufficiently to control the 25 passage of the types.

25 In the accompanying drawings, Figure 1 is a side elevation of the receiving end of my improved type-containing channel with the cord in place; Fig. 2, a plan of the same; Fig. 3, a 30 side elevation of the same end of the channel without the cord; Fig. 4, a longitudinal section upon plane of line $v v$, Fig. 2, without the cord; Fig. 5, a like view with the cord in position; Fig. 6, a horizontal section of the end 35 of the channel upon plane of line $w w$, Fig. 5, illustrating the utility of the longitudinal slot in applying the cord; Fig. 7, a side elevation of the receiving end of the channel, containing a short line of types and my improved 40 type-preceder; Fig. 8, a plan of the parts shown in Fig. 7; Fig. 9, a side elevation of my improved slug or type-preceder; Fig. 10, an edge view of the latter; Fig. 11, a section of the slug or preceder upon plane of line $x x$; Fig. 9; Fig. 12, a section of the same upon plane of line $y y$, Fig. 10. Fig. 13 is a transverse section of the channel upon line $z z$, Fig. 4.

45 The containing-channel A is preferably made of sheet metal stamped up into the required form by suitable dies, &c., as heretofore. At the type-receiving end the extremity of one wall is formed with the slit b. This slit is formed in the edge of the side wall of the channel A, to which the cord C is applied—preferably the high wall a—although, if desired, the cord C may be applied to the low wall a' of the channel. The position of the slit b is regulated so that the knot c of the cord 50 C, when the latter is in position, will be either above or below the area traversed by the "pusher" when the channel is connected with

the distributor. The parts are usually arranged in such manner that the pusher-fingers enter the receiving ends of the channels about 70 midway of the height of the high wall a, or one-half of "type-high," so as to act upon the middle of the types at or approximating a right angle to their length. For this reason I have shown in the drawings the slit b formed in the 75 end of the side wall a above the field of action of the pusher, although it may be otherwise situated thereon, or may, if preferred, be formed directly in the end of the bottom or spine a' , in lieu of the perforation heretofore used at that point.

80 At or near the middle wall a the two perforations $b' b''$ are formed equidistant from the floor or spine a' , so that the section c' of the cord C, which projects into the channel between them, will extend longitudinally in the channel. The distance between the inner end of the slit b and the first perforation, b' , is regulated so as to leave sufficient space between the interior projections of the cord C at 85 these points to constitute a free and unobstructed type-receiving space, s, into which the types drop from the lower ends of the conduits in the distributor. In the opposite side wall a' , coinciding horizontally with and parallel to the position of the section c' of the cord C when in place, is formed the longitudinal slot d, preferably slightly larger in width than the diameter of the perforations $b' b''$ in the high wall a.

90 In applying the cord C the knotted end c is slipped into the slit b, so that the knot projects into the channel, and the free end c' first passed through the perforation b' and through the longitudinal slot d in the opposite wall, 95 and then returned through the said longitudinal slot d and passed through the final perforation, b'' . This operation will be understood by reference to Fig. 6, in which the free end c' of the cord is represented as having just 100 been passed through the second perforation, b' , the middle section, c', of the cord being accommodated by the longitudinal slot d.

105 The use of the slit b and the longitudinal slot d in conjunction with the perforations $b' b''$ simplifies and facilitates the operation of applying, removing, or substituting the cords, since heretofore, owing to the narrowness of the channels, the insertion of the free end into the final perforation, b'' , was a tedious and difficult undertaking, requiring skill upon the part of the workman, whereas by my present construction the cords may be applied by distributor-boys or others of slight experience.

110 The type-preceder or slug P is formed of a thickness equal nearly to the full width of the type-passage, and one or more of its edges are provided with an elastic or semi-elastic bearing surface of rubber or other suitable material for the purpose of increasing frictional contact with the bottom or spine a' of the containing-channel. The frictional material p is 115 preferably applied in the form of a band, and the perimeter of the slug is preferably grooved 120

to receive and retain the material against lateral displacement. The grooves $p' p'$ are made shallow upon the edges from which it is desired that the frictional material shall protrude, while the grooves $p^2 p^2$ in the other edges are made sufficiently deep to receive and isolate the portion of the band engaging therewith. This construction is illustrated in Figs. 9, 10, 11, and 12, and is for the purpose of producing a reversible slug, the two ends $p^2 p^2$ of which present metallic surfaces to the types, while the other edges present contact-surfaces, which tend to retard the movement of the slug within the channel.

15 In order to support the inner sections, c' , of the cord laterally, I form a shallow groove, c^3 , between the perforations $b' b'$, when desirable. Cord of sufficient thickness to project a suitable distance beyond the inner plane of the 20 wall is used, as shown in Fig. 13.

What I claim as my invention, and desire to secure by Letters Patent, is—

1. A type-containing channel, substantially such as designated, formed with the slit b , in 25 combination with the perforations $b' b'$, ar-

ranged substantially in the manner and for the purpose described.

2. A type-containing channel, substantially such as designated, formed with perforations for the cord C in one side wall, and with the coinciding longitudinal slot d in the opposite side wall, for the purpose and substantially in the manner described.

3. In combination with a type-containing channel, substantially such as described, a type-preceder or slug formed with a soft or semi-elastic frictional surface upon its edge or perimeter in such manner as to increase its frictional contact with the bottom or spine of the said channel, substantially in the manner and 40 for the purpose described.

4. A type-containing channel, substantially such as described, formed with the longitudinal groove c^3 , for the reception of the interior section, c' , of the cord C, substantially in the 45 manner and for the purpose described.

A. AUGUSTUS LOW.
